RECEPTACLE CLOSURE CAP

Filed March 29, 1928

UNITED STATES PATENT OFFICE

HARRY INGRAM, OF BROOKLYN, NEW YORK

RECEPTACLE-CLOSURE CAP

Application filed March 29, 1928. Serial No. 265,656.

My invention relates to closures for bottles, jars, tumblers, or other containers. It has among other objects to provide a closure cap and also a gasket associated therewith in which the cap is formed at its top peripheral edge with a recess to receive the upper edge of the gasket and the latter formed with an upwardly inclined external face or surface providing a tapering portion adapted 10 to fit in the recess at the peripheral edge of the cap so that when the cap is in its depressed or closing position the reduced or tapered upper edge of the gasket will be seated in the recess of the cap with sealing effect and the top proper of the cap will seat or rest upon the top edge or rim of the container whereby a more effective seal is provided between the cap and the container.

The preferred details of formation of 20 the cap and of the gasket will be hereinafter fully described and advantages gained set forth, reference being had to the accompanying drawing forming a part hereof and wherein is illustrated the preferred embodiment of the invention, and in which

Figure 1 is a side elevation, partly in section, of a container or tumbler, showing the cap and gasket as they appear in the final stage of closure;

Figure 2 is a side elevation of the closure cap, in one form thereof;

Figure 3 is a vertical section, enlarged scale, through the closure-cap and the gasket, showing the relation of the two prior 35 to being applied to the container;

Figure 4 is a vertical section, enlarged scale, through the upper portion of a container, and the cap and gasket, when the cap and gasket are in final closing position;

Figure 5 is a side elevation of the upper portion of a container or receptacle, showing the cap with one form of unsealing tab applied to the skirt of the cap;

Figure 6 is a similar view showing another 45 form of unsealing tab;

Figure 7 is a vertical section through a modified form of cap and gasket.

In the drawing, the improved cap is designated generally by the reference letter A. 50 This improved cap is formed with a de-

pressed plane or top surface 1 extending to within a relatively short distance of its outer peripheral edge at which point it is slightly raised above the plane of the flat depressed portion as indicated at 3, and then 55 extended outwardly and downwardly, as indicated at 4, preferably at a 45 degree angle, more or less, which angle may be varied, so as to form a recess 5, preferably of substantially inverted V-shaped formation as illustrated. The skirt portion 6 of the cap extends downwardly from the portion 4 and at its lower portion is deflected or inclined inwardly and downwardly as indicated at 7, where it merges into the lowermost depending portion 8 as shown.

With the cap there is used a gasket B, of rubber or other suitable elastic substance. This gasket is formed at its upper portion with an inclined face 9, extending downwardly and outwardly, giving an external bevel to the upper part of the gasket so that the bevel face will fit against the inclined portion of the cap, and forming a relatively thin or reduced terminal 10 to the upper end 70 of the gasket adapted to fit in the recess 5 of the cap as illustrated in Figure 3 of the drawing. The lower end of the gasket is preferably formed with a beveled or inclined face or edge 11 as shown in the same figure, 75 which illustrates the position of the gasket in the cap previous to the cap being applied to the container or receptacle and pressed to its closing position, the edge of the lower beveled portion of the gasket resting upon 80 the seat or inclined portion 7 of the cap skirt and the terminal of the upper beveled portion of the gasket fitting in the peripherally formed recess 5 of the cap as shown in Figure 3.

The inner diameter of the annular gasket is somewhat less than the outer diameter of the neck or mouth of the container or receptacle, and when the cap and its gasket are applied and pressed down with the inner surface of the gasket in contact with the wall of the container, the gasket will be forced into the space between the inclines 4 and 7 of the cap and deformed, as illustrated in Figs. 1 and 4 of the drawing, so as to make a close 85 90 95 100

or tight seal between the wall of the container or receptacle and gasket. It sometimes happens that some foreign substances get in between the cap and gasket, or the gasket and wall of the receptacle, and prevent an effective seal. Again, imperfections occur in the side walls of the container or receptacle at or near the rim, or other part of the container, which also interferes with the sealing. By forming the upper end of the gasket beveled or tapered as described, these imperfections are taken care of so as not to interfere with making an effective seal. With the cap and gasket formed as described, when the cap is forced down on the container or receptacle, contact is first made between the lower beveled portion of the gasket and lip or rim of the container or receptacle which slightly distorts the gasket at that stage as the lip of the container or glass enters the gasket, and at the same time the pressure effecting such distortion forces the relatively reduced or thin portion of the upper bevel or taper of the gasket into the groove at the periphery of the cap, resulting in an effective seal at such point, and at the same time holding the tapered portion of the gasket in the groove and preventing it from curling over the top of the lip or rim of the container or receptacle between the lip and flat top portion of the cap, and thus insuring the top flat portion of the cap resting directly upon the rim of the container or receptacle with the reduced end of the gasket filling the V shaped recess in the cap and excluded from between the flat top of the cap and its seat on the lip or rim of the receptacle.

Furthermore, it is to be noted that with the gasket formed with the taper to make a relatively thin or reduced edge at the top of the gasket, the relatively thin or reduced edge of the gasket accommodates itself more readily to inequalities that may exist in the cap than would a materially wider top surface to the gasket and hence a more easily made and more effective seal obtained, and with less pressure required for forcing the cap to its closing position. The relatively reduced or thin edge thus given to the gasket also results in less back pressure by the gasket on the cap than would be exerted by a materially wider gasket bearing against the cap, with less danger from back pressure releasing the seal. Again, it will be observed that since the gasket lies between the inclined portions 4 and 7 of the cap skirt, with its tapered ends bearing against the inclined portions 4 and 7 of the cap, the downward travel of the cap will force the gasket outwardly into the space or cavity between said inclined portions which exert pressure in opposing directions on the gasket so as to make closer contact between the gasket and wall of the container or receptacle and thus make a tighter seal.

The foregoing statement of reasons for forming the cap and also the gasket with the novel features specified make apparent, advantages resulting from the invention made.

A modified form of the invention is given in Figure 7 of the drawing, wherein A' represents the cap having a depressed flat top surface 1a, formed at its peripheral edge with a slightly raised portion 3a which with the skirt portion 6a forms a substantially inverted V-shaped groove 5a lying outside of the flat top of the cap which will seat on the lip or rim of the receptacle, the tapering groove being adapted to receive the relatively thin or reduced terminal 10a of the beveled or tapered face of the gasket B', the skirt 6a of the cap having the downwardly and inwardly inclined portion or shelf 7a upon which will bear the lower end of the beveled portion 11a of the gasket, the gasket being forced into the space or cavity of the skirt between the inclined portions 3a and 7a of the cap on forcing down the cap so as to deform the gasket and effect a seal between it and the container to which the cap and gasket are applied.

While the form of the invention illustrated in Figures 1 to 4 is preferred the modified form illustrated in Figure 7 can be used to obtain some of the advantages set forth for the preferred form.

The cap illustrated in Figure 5 shows a tab 11 with an aperture 12 to receive a tool for engaging the tab to pull on it so as to tear or fracture the skirt for breaking the seal in removing the cap; and in Figure 6 the numeral 13 indicates another form of tab for breaking the seal and removing the cap, but such special features are not claimed herein.

Illustration of the preferred details of construction have been given and described, but changes therein can be made without departing from the invention as sought to be defined by the annexed claims.

The cap will be formed of relatively thin or flexible metal, such as aluminum, or other thin and flexible metal, or other suitable material.

Having described the invention and set forth its merits, what I claim is:

1. A receptacle closure comprising a cap having a depending skirt formed at its lower portion with a downwardly and inwardly inclined part to form an inclined seat for an outer edge of a gasket having a lower beveled face and formed between its upper portion and the top proper of the cap with an inclined part to form an inclined seat for an upper beveled face of the gasket, said upper and lower inclined seats serving to distort the gasket into sealing relation between the cap and container in moving the cap to sealing position and also permitting the cap to seat upon the lip or rim of the container with

the gasket excluded from between the cap and its seat.

2. A receptacle closure comprising a cap having a depending skirt formed at its lower portion with a downwardly inclined part to form an inclined seat, and at its upper portion, between it and the top proper of the cap, with an inclined part to form an inclined seat, the cap being also formed with a peripherally disposed raised portion having on its inner face an annular recess with an inclined wall; and a resilient wedge-shaped gasket having beveled upper and lower ends and disposed to have its upper beveled face bear against the upper inclined seat of the cap and the terminal of the upper beveled end fit in said annular recess, the inclined upper and lower seats serving to distort the gasket into sealing relation between the cap and container in moving the cap to sealing position, and the annular groove in the cap serving to exclude the gasket from between the cap and its seat and permit the under face of the cap to seat upon the lip or rim of the container, the annular groove in the cap being retained when the cap is in sealing position.

3. A receptacle closure cap having a depending skirt and formed with a peripherally disposed annular raised portion formed on its under face with an annular tapering recess, the upper portion of the cap having an inclined portion below said recess, and a resilient gasket having an inclined face at its upper end bearing against said inclined portion of the cap and formed with a tapering upper edge fitting in the tapering recess of the cap, said recess upon compression of the gasket in forcing the cap into closing position serving to guide the compressed gasket into the recess and prevent its spreading between the under face of the cap and portion of the receptacle upon which the cap seats and effecting a seal at such point.

4. A receptacle closure cap having a depending skirt and formed with a peripherally disposed annular raised portion formed on its under face with an annular recess having an inclined wall, the skirt of the cap at a lower plane than said wall having an inwardly and downwardly inclined off-set portion, and a resilient gasket having the edge of its upper end an inclined face bearing against the inclined wall of the recess and at its lower end bearing against the inclined off-set portion of the skirt, the gasket adapted to be compressed between said inclined wall and off-set portion upon forcing the cap into closing position for effecting a seal between the gasket and adjacent wall of the receptacle.

5. A receptacle closure cap having a depending skirt and formed with a recess on the under face of the cap, the skirt being formed at its lower part with an inner in-

clined off-set portion, and a resilient gasket having an external beveled upper edge to fit in the recess of the cap and a lower inner beveled edge to bear upon the inclined off-set of the skirt, the gasket adapted to have its upper beveled edge compressed into the recess of the cap when the cap is forced into closing position and effect a seal between the gasket and recessed portion of the cap and also between the gasket and adjacent wall of the receptacle.

In testimony whereof I affix my signature.

HARRY INGRAM.
